UNITED STATES PATENT OFFICE.

PHILIPPE DE CLAMECY, OF BOSTON, MASSACHUSETTS, ASSIGNEE TO CORONA TYPE-WRITER COMPANY, INC., A CORPORATION OF NEW YORK.

TYPE-WRITING MACHINE.

1,278,877.

Specification of Letters Patent. Patented Sept. 17, 1918.

Application filed March 6, 1916. Serial No. 22,406.

To all whom it may concern:

Be it known that I, PHILIPPE DE CLAMECY, a citizen of the United States, and a resident of Boston, county of Suffolk, and State of Massachusetts, have invented certain new and useful Improvements in Type-Writing Machines, of which the following is a full, clear, and exact description:

This invention relates more particularly to an escapement mechanism for a foldable front-strike or other typewriting machine.

One of the principal objects of the invention is to provide a simple and efficient escapement mechanism which is operatively connected to key-operated levers and which has parts thereof so mounted that one part of the escapement mechanism is adapted to separate from another part and fold with the platen carriage rearwardly and downwardly within the main frame of the machine to a more compact position and out of operative relation with the key-operated levers, said separable part of the escapement mechanism being adapted to move with the platen carriage from an inoperative position and automatically placed into coöperative relation with the other part of said escapement mechanism to adapt the escapement mechanism to be operated and the letter-feed movement of the carriage controlled as the keys are depressed.

Another object of the invention is to provide a typewriting machine wherein type-bars and the escapement mechanism may be operated by two-part key-operated levers and the escapement mechanism only operated by two-part space bar levers, one part of which are foldable relatively to another part.

Other objects of the invention are to provide a typewriting machine wherein the space bar forms a part of a keyboard and is adapted to fold as a part of the keyboard to a compact position; to provide means whereby the space levers and key-operated levers may be held to fold and unfold together; and to provide a typewriting machine in which the space bar is foldable and has a common axis with foldable parts of key-operated levers, and which space bar is adapted to operate the universal bar independently of the printing instrumentalities.

A further object of the invention is to provide a typewriting machine wherein the

carriage, tension mechanism and a part of the escapement mechanism may be given a vertical shift movement.

A still further object of the invention is to provide a simple and efficient escapement release to adapt the carriage to move freely transversely of the machine.

With these and other objects in view, the invention will be hereinafter more particularly described with reference to the accompanying drawings, which form a part of this application, and will then be pointed out in the claims at the end of the description.

In the drawings, Figure 1 is a longitudinal section, partly in elevation, of one form of the machine embodying the invention.

Fig. 2 is a plan view, partly broken away.

Fig. 3 is a front elevation.

Fig. 4 is a fragmentary view, partly broken away and partly diagrammatic, of a part of the escapement actuating means.

Fig. 5 is an enlarged fragmentary side elevation of a part of the escapement operating means.

Fig. 6 is a side elevation of a part of the mechanism shown in Fig. 5.

Fig. 7 is an enlarged fragmentary sectional view, showing in side elevation the knee-joint forming a connection between the two parts of the space bar levers and the key-operated levers; and

Fig. 8 is an enlarged fragmentary section, showing means for holding the platen carriage and escapement against folding movement.

The main frame or main frame part 10 has upright corner pillars or posts 11 with the usual rubber tips or feet 12 and connecting the posts at the lower portion thereof is a base 13. At the upper portion of the main frame part is a top plate or member 14 and there may be side plates if desired, it being understood that the frame, or main frame part, may be of the usual or of any preferred construction. At the forward portion of the machine is a keyboard frame part 15. This keyboard frame part 15 is hinged at 16 to the main frame part and at the outer portion thereof may be provided with rubber feet of the usual kind. The keyboard frame part 15 is tray-like in form and is adapted to fold upwardly and inwardly as shown in dotted lines in Fig. 1. The hinge or pivot 16 is in

the form of bolts located on opposite sides of the main frame part in alinement, and said bolts have threaded stems which are engaged by thumb nuts 17 which assist in holding the keyboard frame part in its folded and in its normal operative position. This keyboard frame part 15 at its inner portion is provided with an abutting surface 18 which is adapted to engage a substantially L-shaped spring 19 secured to the frame base 13 so as to position and hold said frame part in a normally horizontal position, and in the folded position of said frame part the latter is retained in such position by means of a spring 20, one end of which is secured to the under surface of the frame part 13 or otherwise held as desired, the thumb nuts 17 serving as additional holding means for said frame part.

20 A keyboard 21 is mounted to move with the keyboard frame part 15. This keyboard may be of a universal or standard kind and comprises keys 22 which are arranged in banks or groups and are mounted upon the upper ends of vertical portions of levers 23. The levers 23 are each formed in two parts 24 and 25. The parts 24 and 25 are in alinement when in a normal operative position and all of the parts of said levers are pivotally held to a transversely extending rod 26. The rod 26 is held in a main frame part of the machine between the forward corner posts 11 of the main frame part or in any other desired way. The parts 25 of the key-operated levers extend horizontally and are in alinement with the horizontal portions of the parts 24, and on one of said parts, as the part 24 of each lever, is a shoulder 27 which is adapted to engage a shoulder 28 of the part 25 when in normal operative position as shown in Fig. 1, so that on the depression of one of the keys 22 the inner end of the part 25 of the two-part lever on which the key is mounted will be forced upwardly. 45 Each lever 23 is restored from a depressed position to its normal operative position by a spring 29, one end of which is secured to the base 13 and the other end passed through an aperture in the key lever part 25. The 50 shoulders 27 and 28 and the mountings of the parts 24 and 25 provide a knee or knuckle joint which adapt all of the parts 24 of all of the key-operated levers to fold relatively to the parts 25 as shown in dotted lines 55 in Fig. 1.

The inner ends of the parts 25 of the key-operated levers 23 each have a pin 30 and each pin is adapted to move in a slot 31 of an arm 32. The arm 32 forms a part of the 60 bell-crank lever 33 and each bell-crank lever is pivotally held in a bracket 34 extending upwardly from the base 13 or to a common pivot rod as preferred. The arm 35 of each bell-crank lever 33 is pivotally held by a 65 knee or other joint at its outer end 36 to an

upwardly extending link 37, and said link 37 at its upper end is pivoted at 39 to the short arm 40 of a type-bar 41. Each type-bar 41 is adapted to have a plurality of type or characters thereon according to whether 70 a single case shift or double case shift is employed. The type-bars are adapted to rest at their forward ends upon a felt, rubber or other cushion 42 and are arranged in a curved path within the type basket 43, said 75 type basket being suitably held in the main frame part of the machine in such a way that when a key-operated lever is moved on the depression of a key, the actuation of its co-operating bell-crank lever 33 will force a 80 link 37 downwardly and this will cause one of the type-bars to move the type upwardly and rearwardly to make an impression upon the work sheet about the platen 44 in the usual way.

85 As a means to lock the keys and the foldable parts of the key-operated levers to fold and unfold together, a bar 45 extends transversely of the machine over the parts 24 and under the parts 24 is a substantially U-shaped rod 46. The rod 46 is pivotally mounted between the sides of the shallow frame part 15 and is adapted to be forced to the position shown in dotted lines in Fig. 1 so that the transversely extending portion 90 47 will lie directly under the parts 24 of the key-operated levers thus holding the parts 24 of said levers which fold between the transversely extending bar 45 and the portion 47 and thereby prevent their disarrangement. The bar 45 may have a rubber or other strip forming an engaging surface for the key-operated levers, and the rod 46 may have a knob or handle to move the same, it being understood that the key-lever parts 100 24 are not held so tight between the bars 46 and 47 as will prevent such relative movement of the keyboard frame part 15 and the key-lever parts 24 as is necessary because of their different pivot points. If desired the 110 pivots of the levers and the keyboard frame part may have a common axis or pivot rod or shaft.

115 The platen 44 is mounted upon a platen carriage 48. This platen carriage 48 is adapted to travel transversely of the machine on a foldable support 49. This support 49 has two members 50 and 51 which are hinged together at 52 at the upper portion of the machine. The support member 120 50 rests when in a normal operative position upon a transversely extending bar 53 forming a part of the vertically movable member 50 of the platen carriage support. The platen carriage may be variously constructed. As shown it comprises end pieces or brackets 54 which extend upwardly from a carriage base 55 and said base may be held to travel transversely of a carriage bed. 125 The carriage bed may extend rearward as 130

far as the hinge 51 or may be supported between foldable arms or in other desired way. The carriage end pieces 54 support the axis or shaft 56 of the platen and said end pieces 5 may also support a paper apron 57 in which may be mounted a pressure or feed-roll 58, there being paper fingers and such other parts as are usually employed to hold and guide the work about the platen.

10 While the platen carriage with its bed forming one member of the carriage support is adapted to fold rearwardly and downwardly so as to extend within the main frame part 11 and between the sides thereof 15 when in a compact position as shown in dotted lines in Fig. 1, the platen carriage and both members of the support are adapted to be shifted for upper case characters when in a normal operative position, though it will 20 be understood that the platen carriage may have two shift movements instead of one, or the type basket itself may be shifted as in some forms of writing machines, if desired. The movable carriage support member 50 25 at each end has upright portions 59 and these portions 59 have a tongue and groove or other connection with the sides of the main frame part 11 or otherwise held to move vertically thereon so that in its vertical 30 movement the platen carriage with its bed 55 will partake of such vertical movement. A pin or stud 60 projecting inwardly from each side of the main frame part 11 enters a slot 61 in each carriage support portion 59 and adapted to engage the lower edge of said portion 59 of the carriage support is an eccentric 62. There may be an eccentric on each side of the machine connected by a shaft 63 to adapt a uniform 35 movement to be given to the carriage support without canting or twisting the same, and said shaft 63 is journaled in brackets 64 on the frame base 13. An arm 65 extends upwardly from the shaft 63 at each side of 40 the machine and connected to each arm 65 is a link 66. Each link 66 is connected to an arm 67 of a bell-crank lever which is mounted in the bracket 34 on the same rod as the bell-cranks 33 are mounted. A shift 45 lever 68 is located at each side of the machine so that the platen carriage may be shifted from either side of the keyboard, and each shift lever comprises two parts 69 and 70, which have a knee joint connection 50 similar to the key-operated levers 23 in order that said shift levers may have one part fold 55 relatively to the other part and the foldable part thereof movable as a part of the keyboard when the keyboard frame part is folded to its compact position. The parts 70 of the shift levers are adapted to operate the bell-crank arms 67. These arms or either of them operate the links 66 and the eccentrics 62 on the depression of the shift keys, and 60 this movement of the eccentrics 62 forces the

carriage support members 50 and 51 to place the printing point and the platen in position for writing upper case characters.

The platen carriage and its support may be held in its normal operative position against relative backward folding movement in any desired way. As shown, a pin or stem 71, Figs. 2 and 8, has a knob or head 72 thereon and is normally forced inward by a spring 73. The pin 71 is adapted to engage an aperture 74 in one end of the carriage bed or other part and lock said bed to the vertically moving supporting member 50 so that the platen carriage cannot fold rearwardly until the pin is released. The platen carriage may also be held against a swinging or free movement when in its folded compact position by a releasable pin or part 74^a or otherwise, which is held to the frame of the machine and is adapted to engage under a part of the foldable carriage supporting member 51 when in its compact position as shown in Fig. 1.

As an escapement operating mechanism to control the letter-feed movement of the platen carriage and means to operate said mechanism a universal bar 75 is provided, which is adapted to overlie the inner ends of the key-operated levers 23. This universal bar extends transversely of the machine and has upwardly extending ends 76 which are guided in tubular posts or guides 77. The universal bar is normally forced downwardly in the path of the key-levers 23 by springs 78. The universal bar has inwardly extending arms 79 and these arms extend upwardly, as at 80, at opposite sides of the machine. At the upper ends of the parts 80 are heads or slides 81 and 82. These heads 81 and 82 are suitably guided at their upper ends by brackets 83 or otherwise, and said heads are adapted to engage rollers 84 and 85 respectively, both of which are mounted upon a transversely movable rod 86. The rod 86 is suitably supported in the machine frame and is normally forced against the action of the heads 81 and 82 by one or more springs 87. The heads 82 are each provided with a straight portion 88 forming a normal seat for the rolls 85 and a beveled or inclined part 88^a forming a wedge-like actuating part on each head. Pivoted to each head is a pawl or dog 89. The pawls 89 have their free ends normally forced outwardly beyond the heads 80 to provide teeth 90, and each tooth is adapted to move inwardly within a recessed part of the head during the upward movement of the heads and rods 86 on the depression of the key-operated levers. A spring 91 tends normally to force each pawl 89 outwardly or permit the pawls to be moved inwardly during the upward movement of the heads. The upward movement of the heads will cause the rolls and rod 86 to move trans-

versely of the machine to a point indicated by the first dotted line of roll as at 91^a, Fig. 5. As the pawls 89 are forced above the rolls 84 and 85, owing to their being held to yield, they will not operate said rolls but immediately that the teeth of said pawls are above said rolls the teeth or ends 90 thereof will engage the upper portion of the rolls, and during the downward movement of the 10 universal bar and heads 82 an additional throw will be given to said rod 86 to the point indicated by dotted roll 91^b, said pawls being each held against upward movement by means of a stop or part 92 located immediately above said pawls. Two lugs or projections 93 which are spaced apart and project rearwardly from the transversely movable rod 86 are adapted to span an arm 94 of an escapement detent or arm 95. The 20 detent 95 is pivoted at 96 and has a retaining tooth or dog 97 and a longer tooth or dog 98 which are adapted alternately to engage the teeth of a rack 99 by reason of the reciprocatory movement of the rod 86. The 25 dog 97 is released during the additional throw given the rod 86 by the pawls 89 and this will place the longer dog 98 in engagement with the rack, said dog 98 being released on the return movement of the rod 30 86 and the universal bar. The rod 86 may be operated on the downward movement of the pawls 89 instead of partly on the upward movement of the heads 81 and 82 thus avoiding any lost motion between the projections 93 and arm of the detent 95, in which case said heads do not move the rod 35 86 on their upward movement and the wedge portions are dispensed with. The rack 99 is supported under the platen carriage and 40 may be pivoted at one end, as at 100, to adapt the escapement rack to be released from the escapement dogs, as will be presently described. The platen carriage is normally under tension of a spring in a 45 drum 101, mounted under the carriage supporting members to shift therewith, and is adapted through the usual strap or connection to move the carriage a letter space each time the universal bar is operated, though 50 instead of the particular form of mechanism shown a limber and fixed dog adapted alternately to engage the rack teeth, as is common in many forms of typewriting machines, may be employed and operated by 55 the rod 86 or in any other desired way. By having the universal bar actuate the reciprocating bar 86 on its downward movement rather than its upward movement the letter feed movement of the carriage takes place 60 at a time after the type have moved against the work on the platen; otherwise the carriage might move at or about the time an impression is made by the type. The rod 86 may be made to reciprocate from right to 65 left instead of left to right to release the

escapement, in which case the dog 98 will normally engage the rack. The heads 81 and 82 and rolls 84 will in that case be reversed to move the rod 86 in a direction opposite to that shown. 70

It will be evident that the escapement dogs and rack which are both mounted upon the platen carriage support may by reason of the arm 94 resting between the projecting lugs or parts 93 on the transversely extending rod 86 be separated therefrom when the platen carriage and its supporting bed are moved to a compact position, and on the platen carriage being restored to its normal operative position the arm 94 will automatically position itself between said lugs or projections 93 ready to be operated when the keys and universal bar are operated. 75

The carriage may be letter spaced without printing in any suitable way. The space bar 102 is connected to levers 103. These levers 103 are divided into two parts, 104 and 105, and said two-part levers are mounted upon the transversely extending rod 26 and have a knee-joint connection similar to 80 the key-operated levers 23, so that the space bar and the forward parts 103 of the two-part levers may fold and unfold as a part of the key-board, and may be locked between the bar 45 and rod 46 as is the case 85 with the key-operated levers 23. The inner parts 105 of the key-operated space levers simply actuate the universal bar and have no connection whatever with any of the printing instrumentalities. 90

The carriage may be released to permit the same to move freely along its bed. As one means a bell-crank lever 106 is pivotally held to one of the carriage end brackets 54. This lever 106 is pivoted at 107 and has one arm thereof formed as a finger portion 108. The other arm of said lever is slotted as at 109, to engage a pin 110 on the carriage rack. This pin 110 is slidably held in the carriage end bracket and is normally forced in one direction by a spring 111 arranged in a slot 112, said rack, as before stated, being pivoted at its end opposite the part engaged by the lever 106. As the lever 106 is depressed the rack will be shifted to one 110 side and be released from the teeth of the escapement dogs thus permitting the carriage to be moved freely in either direction along the carriage bed. 115

In the drawings a special form of ribbon 120 mechanism is shown, but such mechanism is neither described nor claimed herein as it forms subject matter of another pending application.

Having thus described my invention, I 125 claim as new and desire to secure by Letters Patent:—

1. In a typewriting machine, the combination of a frame, a platen carriage supported therein, escapement mechanism, a 130

rod supported to move transversely of the frame to actuate the escapement mechanism, a vertically movable universal bar, and means actuated by the universal bar for reciprocating said rod transversely of the frame.

2. In a typewriting machine, the combination of a frame, a platen carriage movable transversely of the frame, a rack movable with the carriage, escapement dogs adapted to engage said rack, tension mechanism for the carriage, a vertically slideable universal bar supported in the frame, transversely slideable means for actuating the escapement mechanism, connections between said bar and said transversely moving means for shifting the transversely moving means in one direction, yieldable means for normally holding the universal bar in lowered position, and yieldable means normally tending to move the escapement actuating means in a direction opposite to that in which it is moved by said universal bar.

3. In a typewriting machine, the combination of a frame, a platen carriage, escapement mechanism, reciprocable means for actuating the escapement mechanism, a reciprocable universal bar, and means carried by said universal bar for causing said reciprocable means to actuate the escapement mechanism on the return movement of the reciprocable universal bar.

4. In a typewriting machine, the combination of a main frame, a platen carriage movable along said main frame part, tension mechanism for the carriage, a rack movable with the carriage, an escapement detent having dogs adapted to engage said rack, a transversely reciprocatory rod for operating the detent, key-operated levers, a universal bar operated by said levers, and vertically reciprocatory means actuated by the universal bar for moving said escapement operating rod.

45 5. In a typewriting machine, the combination of a frame, a platen carriage, escapement mechanism, reciprocatory means for actuating the escapement mechanism, a reciprocable universal bar, type bars, key-operated levers for actuating the type bars and universal bar, and reciprocatory means carried by the universal bar for causing said reciprocatory escapement actuating means to actuate the escapement mechanism on the return movement of the universal bar.

6. In a typewriting machine, the combination of a main frame part, a platen carriage adapted to move along said main frame part, a foldable carriage-bed, a rack mounted upon the carriage-bed and movable therewith, escapement means engaging the rack to control the letter-spacing movement of the carriage, a rod having means mounted thereon adapted to separably connect the rod to the escapement means engag-

ing the rack, means normally forcing the rod in one direction, rolls carried by said rod, vertically movable rods carrying means for actuating said rods in one direction, a universal bar for operating said rods, and key-operated levers for moving the universal bar.

7. In a typewriting machine, the combination of a frame, a platen carriage, escapement mechanism for controlling the letter-spacing movement of the carriage, a vertically reciprocable universal bar, and means reciprocable transversely of the frame operatively connected to be reciprocated by the vertically reciprocable universal bar for operating the escapement.

8. In a front-strike typewriting machine, the combination of a main frame, a platen carriage adapted to move along said frame, a rack mounted upon the carriage and movable therewith, means engaging the rack to control the letter-spacing movement of the carriage, a rod having means mounted thereon to connect the rod to the escapement means engaging the rack, spring means normally forcing the rod in one direction, rolls carried by said rod, vertically movable rods for actuating said rolls in one direction against the tension of the spring means, a universal bar for operating said rods, and key-operated levers for moving the universal bar.

9. In a typewriting machine, the combination of a main frame, a platen carriage adapted to move along said frame, escapement mechanism, a transversely reciprocatory rod for operating said escapement mechanism, rolls carried by said rod, vertically movable rods having means for actuating said rolls in one direction during the upward movement thereof and for giving an additional movement to said rolls on the reverse movement of said rods to operate the escapement mechanism, a universal bar for operating said rods, and key-operated levers for moving the universal bar.

10. In a typewriting machine, the combination of a main frame part, a platen carriage adapted to travel transversely of the machine on said frame part, escapement mechanism for controlling the letter-feed movement of the platen carriage, a rod operatively connected to the escapement mechanism, means including a spring pressed dog adapted to yield and move past the rod in one direction and engage and move the rod when moving in a reverse direction, a universal bar operatively connected to said means, and key-operated levers for moving the universal bar.

11. In a typewriting machine, the combination of a main frame, a keyboard frame part pivotally connected with the main frame, type bars supported on the main frame, escapement mechanism, two-part key-

operated levers for actuating the type bars and escapement mechanism, a space bar, two-part levers held to the space bar and adapted to actuate the escapement mechanism, all 5 of said two-part levers having a common point of fold out of alignment with the pivotal point of the keyboard frame part, and means for holding one part of each of 10 said two-part levers to the keyboard frame part to fold therewith relatively to the type bars and escapement mechanism.

12. In a typewriting machine, the combination of a main frame, a platen carriage adapted to travel transversely of the machine 15 of said frame, escapement mechanism for controlling the letter-feed movement of the platen carriage, a rod operatively connected to the escapement mechanism, a vertically movable head adapted to operate the rod a 20 certain distance, a spring pressed dog mounted on the head and adapted to yield and move past the rod in one direction without operating the same but to engage and move the rod an additional distance when 25 moving in a reverse direction, a universal bar operatively connected to said head, and key-operated levers for moving the universal bar.

13. In a typewriting machine, the combination of a frame, a platen carriage, escapement mechanism, a slidably mounted rod extending transversely of the frame and operatively connected to actuate the escapement mechanism, a vertically movable head for 35 reciprocating said rod, and a universal bar for operating said head.

14. In a typewriting machine, the combination of a platen carriage, a rack pivotally held at one end thereof and movable with the 40 carriage, means coöperating with said rack to control the letter-spacing movement of the carriage, means engaging the free end of the rack to swing the rack on its pivot out of co-

operative relation with said coöperating means, and yieldable means engaging the 45 free end of the rack for normally holding the rack in coöperative relation with said co- operating means.

15. In a typewriting machine, the combination of a platen carriage, a rack pivotally held at one end thereof and movable with the platen carriage, means coöperating with said rack to control the letter-spacing movement of the carriage, a lever movable with the carriage and having a pin-and-slot 50 connection with the free end of the rack for swinging the rack on its pivot out of co- operative relation with said coöperating means, and yieldable means for normally holding the rack in coöperative relation with 55 said coöperating means.

16. In a typewriting machine, the combination of type-bars, a platen carriage, escapement mechanism for said carriage, a universal bar adapted to operate the escapement 60 mechanism, key-operated levers for moving the type and tripping the escapement, a space bar, and two-part levers held to the space bar and having a knee joint connection to permit the space bar to fold relatively to the type, said space bar levers being 65 adapted to operate the escapement mechanism without moving the type-bars.

17. In a typewriting machine, the combination of a frame, a platen carriage, 70 escapement mechanism, means for actuating the escapement mechanism, reciprocatory means including a spring-pressed dog adapted to yield and move past the escapement actuating means in one direction and to 80 operate said escapement actuating means on the reverse movement, and a universal bar carrying said reciprocatory means.

This specification signed this 2d day of March, A. D. 1916.

PHILIPPE DE CLAMECY.
